(57) **CLAIM**

The ornamental design for surface propeller fishing lure device as shown and described.

DESCRIPTION

FIG. 1 is a perspective view of a fishing lure device, detailing my new design;

FIG. 2 is a first side view of the device of FIG. 1;

FIG. 3 is a second side view of the device of FIG. 1;

FIG. 4 is a top view of the device of FIG. 1;

FIG. 5 is a bottom view of the device of FIG. 1;

FIG. 6 is a front view of the device of FIG. 1; and,

FIG. 7 is a back view of the device of FIG. 1.

The broken line shown of environment and all views are for illustrative purposes only and forms no part of the claimed design.
